UNITED STATES PATENT OFFICE.

CHARLES W. FLIGHTNER, OF BRYAN, OHIO.

LADDER-SUPPORT.

1,007,347.

Specification of Letters Patent.

Patented Oct. 31, 1911.

Application filed March 23, 1910. Serial No. 551,109.

To all whom it may concern:

Be it known that I, CHARLES W. FLIGHTNER, a citizen of the United States, residing at Bryan, in the county of Williams and 5 State of Ohio, have invented certain new and useful Improvements in Ladder-Supports, of which the following is a specification.

This invention relates to ladders and more 10 particularly to supports therefor, and has for its object to provide a ladder support which may be used to hold a ladder in proper position but spaced from the wall which supports it.

15 Another object is to provide a device of this kind which will also serve as a rest to hold material used by the person upon the ladder.

Other objects and advantages will be apparent from the following description, and it will be understood that changes in the specific structure shown and described may be made within the scope of the claim without departing from the spirit of the invention.

20 In the drawings forming a portion of this specification and in which like numerals of reference indicate similar parts in the several views,—Figure 1 is a side elevation of a ladder provided with the present support. Fig. 2 is a front view showing the arrangement of the parts. Fig. 3 is a top plan, and Fig. 4 is a view of the supports detached. Fig. 5 is a modified form of the brace member. Fig. 6 is a modified form of the hook member.

Referring now to the drawings, there is shown a ladder 5, including spaced rungs 6.

The support proper, shown in the drawings, consists of two upper sills 7 and 8, each of which includes an inner vertical flange 9 and an upper outwardly extending horizontal flange 10. The forward ends of these sills 7 and 8 extend parallel to each other, as shown at 11, these parallel portions being relatively short, and the rearward portions of the sills being diverged as indicated. At a point spaced from the rearward ends of the sills, a transversely extending connecting 45 brace 12 is attached thereto, and diagonal brace members 13, secure this brace 12 to the sills. Secured in the angles of the flanges 9 and 10 at the straight portions 11 of the sills, there are the stems 13 of yokes 14, each 50 including an upper arm 15 and a lower arm 16, the two arms being connected by a bite

portion 17 as shown. These arms are arranged for engagement with one of the rungs 6 of the ladder, and, as shown, they have openings 18 therein adjacent to the ends of their arms for the reception of retaining pins 19, these pins holding the yokes against disengagement from the ladder rungs. The pins 19 are tapered, and the openings 18 of the arms 16 are correspondingly smaller than the openings of the arms 15, to receive the tapered end portions of the pins. The pins have notches 21, which are arranged to engage beneath the rung of the ladder after the pins have been inserted in position, so that they are held against casual displacement, although they may be manipulated to remove them as will be understood.

Pivoted to the vertical flanges 9 of the sills 7 and 8, rearwardly of the brace 12, there are a pair of supporting bars 22 which extend downwardly and forwardly as shown. Each of these bars is provided adjacent to its lower end with a longitudinal series of perforations 23, as shown. A pair of hook members 24 are provided, each of these hook members including a bifurcated shank 25 engaged upon the corresponding supporting bar 22, and these shanks are provided with openings 26, arranged for the removable reception of pivot pins 27 which may thus be engaged in any one of the openings 23, and the hook members thus shifted longitudinally of the supporting bars. As shown in the drawings, the hooks extend upwardly, and are engaged with one of the rungs of the ladder below the rung with which the yokes 14 are engaged, thus supporting the bars 22.

In the modified form of the invention, the hook members are illustrated at A and include oppositely directed hooked ends B and C, connected by a portion D provided with a passage E, which receives one of the bars 22, and which has openings F for the reception of the pivot pins. The position of this hook makes the attachment of the bars 22 with the rungs possible under different conditions. Also in the modified form of the invention, the brace member 12 consists of two sections G and H, adjustably connected so that the rearward ends of the sills 7 and 8 may be shifted toward and away from each other.

In use, after the yokes and hooks have 110 been engaged with the rungs of a ladder, the sills 7 and 8 will extend rearwardly as illus-

trated, and their rearward ends may be allowed to rest against the wall of a house or other support in connection with which the ladder is to be used. The sills will then extend horizontally, and can be used as supports for materials to be used by the person on the ladder. By shifting the relative position of the hooks 24 the slant of the ladder may be varied.

10 What is claimed is:

A ladder support comprising upper sills occupying a common horizontal plane, said sills having parallel forward portions and rearwardly divergent rearward portions, each of said sills including an inner vertical flange and an upper outwardly extending horizontal flange, yokes having stems secured in the angles of the flanges at the straight portions of the sills, said yokes having arms extending forwardly and being arranged for engagement with a rung of a ladder, said yokes having openings ad-

jacent to their free ends, pins arranged for removable engagement in the openings, a brace bar for the rearward portions of the 25 sills, downwardly and forwardly extending bars pivoted to the sills rearwardly of the brace bar, said bars having each a longitudinal series of perforations in its forward portion, hook members having bifurcated 30 stems engaged upon the forward portions of the diagonal bars, said bifurcated stems having openings therein arranged for interchangeable registration with the openings of the diagonal bars, and pivot pins arranged for interchangeable engagement in the registered openings.

In testimony whereof I affix my signature, in presence of two witnesses.

CHAS. W. FLIGHTNER.
